DESIGN FOR A ROUGE BOX

Philip A. Derham and Jesse H. Newport, Jr., Rosemont, Pa., assignors to Victor Metal Products Corporation, Brooklyn, N. Y., a corporation of New York

Application August 15, 1941, Serial No. 102,852

Term of patent 7 years

To all whom it may concern:

Be it known that we, Philip A. Derham and Jesse H. Newport, Jr., citizens of the United States and residents of Rosemont, in the county of Montgomery and State of Pennsylvania, have invented a new, original, and ornamental Design for a Rouge Box, of which the following is a specification, reference being had to the accompanying drawing, forming part thereof.

Fig. 1 is a top plan view of a rouge box showing our new design.

Fig. 2 is a front elevational view of the same.

Fig. 3 is a diametrical vertical sectional view of the same.

We claim:

The ornamental design for a rouge box, substantially as shown.

PHILIP H. DERHAM.
